DESIGN FOR A DRESS

Mildred Wagner, New York, N. Y.

Application April 21, 1938, Serial No. 76,655

Term of patent 3½ years

To all whom it may concern:

Be it known that I, Mildred Wagner, a citizen of the United States of America, residing in the city of New York, county of New York, and State of New York, have invented a new, original, and ornamental Design for Dress, of which the following is a specification, reference being had to the accompanying drawing, forming part thereof.

Fig. 1 is a front view of a dress showing my new design.

Fig. 2 is a rear view thereof.

My design is characterized by the contrasting bands on the shoulders and side portions of the dress in combination with the matching collar revers and matching button holes, on the front portion of the dress as shown.

I claim:

The ornamental design for a dress, substantially as shown and described.

MILDRED WAGNER.
